UNITED STATES PATENT OFFICE.

ISAAC J. JACOB, OF PHILADELPHIA, PENNSYLVANIA.

BASE-BALL-GAME APPARATUS.

SPECIFICATION forming part of Letters Patent No. 738,452, dated September 8, 1903.

Application filed May 5, 1903. Serial No. 155,708. (No model.)

To all whom it may concern:

Be it known that I, ISAAC J. JACOB, a citizen of the United States, residing at the city of Philadelphia, in the county of Philadelphia and State of Pennsylvania, have invented certain new and useful Improvements in Base-Ball-Game Apparatus, of which the following is a specification.

My invention has relation to an improved base-ball game wherein the positions of players are indicated upon a board and the various movements and combinations of movements, both optional and compulsory, of the players are defined on dials in the travel of indicators or pointers by the spinning movements of the same when coming to rest, whereby are the defined either optional or compulsory results or decisions by the exercise of both skill and chance in the play of the game readily ascertained; and in such connection it relates to the construction and particular arrangement of such an apparatus for playing a game of base-ball combining all the features of skill with chance present in the outdoor game.

The nature and scope of my invention will be more fully understood from the following description, taken in connection with the accompanying drawings, forming part hereof, in which—

Figure 1 is a top or plan view of a board upon which the game is played; and Fig. 2 is a top or plan view of the indicating apparatus.

Referring to the drawings, *a* represents a board of preferably square shape and having on its face the representation of a base-ball field. Near one corner of the board *a* is outlined the diamond or players in the field *b*, which is square and has at the corners the representation of home plate *b'*, first base *b²*, second base *b³*, and third base *b⁴*. On the sides of the square *b* are representations of the infield-players' positions during the progress of the game. Thus *d* represents the first baseman, *d'* the second baseman, *d²* the short-stop, and *d³* the third baseman. Within the square *b* is the pitcher's box *e*, within which the pitcher *e'* stands, and in alignment with the pitcher's box *e* and home plate *b'*, outside the square *b*, is the catcher's box *e²*, with the catcher *e³* therein. Adjacent to the plate *b'* is the batter's position *e⁴*, and in the

outfield *a'* is arranged the center and right and left fielders *f*, *f'*, and *f²*, respectively. The board *a* may be creased along the line *a²*, so that it can be folded into smaller compass when not in use. On the field *a* is also indicated the foul-lines *n n*. The movements of the players—infeld, outfield, pitcher, catcher, and batsman, as well as the base-runners—are indicated by a series of three dials *g*, *h*, and *i*, mounted upon a base *m*. Over each dial travels the pointer or arrow *g'*, *h'*, and *i'*. The dial *g*, with its pointer *g'*, indicates the movements or operations of the pitcher, and the dial *g* upon its face shows the various results of the pitcher's efforts, either optional or compulsory, in the play of the game—namely, the giving of bases on balls, the striking out of the batsman, and the times when the batsman connects with the pitcher's delivery by the striking of the ball for sacrifice or other hits. The dial *h*, with its pointer *h'*, serves to indicate the batting and fielding of the opposing players, and the dial *h* therefore has in radial compartments the necessary compulsory combinations of both batting and fielding in the play of the game. The dial *i*, with its pointer *i'*, controls the movements of the base-runners, as clearly indicated upon the face of the dial divided into three defined radial optional compartments in the play of the game.

In the operation of the game the pitcher's dial and indicator are first operated. If the arrow stops at "Struck out," no further manipulation of other dials will follow. If a base on balls is indicated, then the pitcher's dial is again operated, the position of a man on first base *b²* being indicated by a checker or counter. When men are on bases, then the other dials, with their arrows, are manipulated to indicate the progress of the game.

Having thus described the nature and object of my invention, what I claim as new, and desire to secure by Letters Patent, is—

A game apparatus, comprising three members, one member consisting of a board having on one face the representation of a base-ball field, the second member consisting of three dials each having a pointer, one dial with its pointer indicating the operation of the pitcher, that is, the various results optional or compulsory of the pitcher's efforts,

of the giving of bases on balls, striking out batsman and times when the batsman connects with the pitcher's delivery by the striking of a ball for sacrifice or other hitting, the 5 second dial with its pointer indicating the batting and fielding of opposing players and by radial compartments having necessary compulsory combinations of both batting and fielding, and the third dial and its pointer 10 controlling base-runners, being divided into three defined radial optional compartments, and the third member consisting of a device adapted to be moved over the field of the first

member according to certain position or positions of a pointer or pointers of said dial or 15 dials of the different elements of the second member according to rules of the game, when coming to rest, as defined on the dial or dials in such manner.

In testimony whereof I have hereunto set 20 my signature in the presence of two subscribing witnesses.

ISAAC J. JACOB.
